UNITED STATES PATENT OFFICE

GEORGE H. MINER, OF LOS ANGELES, CALIFORNIA, ASSIGNOR TO AMUSEMENT MACHINE CORPORATION, LTD., OF LOS ANGELES, CALIFORNIA, A CORPORATION OF NEVADA

DESIGN FOR A PLAYING FIELD FOR GAME APPARATUS

Application filed August 28, 1931. Serial No. 40,950. Term of patent 14 years.

To all whom it may concern:

Be it known that I, GEORGE H. MINER, a citizen of the United States, residing at Los Angeles, in the county of Los Angeles and State of California, have invented a new, original, and ornamental Design for a Playing Field for Game Apparatus of which the following is a specification, reference being had to the accompanying drawing, forming part thereof.

The figure is a front perspective view of a playing field for game apparatus, showing my new design.

I claim:

The ornamental design for a playing field for game apparatus, as shown.

GEORGE H. MINER.
